United States Patent Office

Des. 225,649

Patented Dec. 26, 1972

225,649

TELEPHONE ANSWERING MACHINE

Charles W. Ho, San Francisco, Calif.
(3144 Somerset Place, Lafayette, Calif. 94549)

Filed Apr. 30, 1971, Ser. No. 139,305

Term of patent 14 years

Int. Cl. D14—03

U.S. Cl. D26—14

FIG_1

FIG_2

FIG_5

FIG_3

FIG_6

FIG_4

FIG. 1 is a view in perspective of a telephone answering machine showing the features of my new design;

FIG. 2 is a bottom plan view of the same;

FIG. 3 is a top plan view of the same;

FIG. 4 is a right side view in elevation of the same which is the same as the left side view;

FIG. 5 is a rear view in elevation of the same; and

FIG. 6 is a front view in elevation of the same.

I claim:

The ornamental design for a telephone answering machine, substantially as shown and described.
